UNITED STATES PATENT OFFICE.

ALBAN H. REID, OF PHILADELPHIA, PENNSYLVANIA.

CHURN CLOSURE.

SPECIFICATION forming part of Letters Patent No. 425,147, dated April 8, 1890.

Application filed January 3, 1890. Serial No. 335,769. (No model.)

To all whom it may concern:

Be it known that I, ALBAN H. REID, of Philadelphia, in the county of Philadelphia and State of Pennsylvania, have invented certain 5 Improvements in Churns, of which the following is a specification.

My invention relates to churns having rotary bodies of angular form; and it consists in improved means for closing the mouth or 10 opening in the side of the body.

Figure 1 is a perspective view of a churn provided with my improvement, the lid being shown detached. Fig. 2 is a cross-section through one side of the body with the lid in 15 place thereon. Fig. 3 is a section on the line xx of Fig. 1. Fig. 4 is an elevation of a detail. Fig. 5 is a similar view of another detail.

In the accompanying drawings, A represents the hollow body of the churn, in the present 20 instance of square form in cross-section, mounted at its ends in journals a in a suitable frame B. The body is provided in one side with a mouth or opening a' , through which the contents are introduced and removed. This 25 opening is encircled by a frame C, bolted rigidly to the body and finishing at the lower side, flush with the inner surface of the body, so that the butter may be withdrawn directly therethrough. The opening is closed by the 30 detachable lid D, a flat plate of metal adapted to fit closely against the outer face of the frame. The lid is held in place by four bolts d and e . The bolts d are provided at their lower ends with horizontal cross-heads 35 of circular form in cross-section, which are seated loosely but snugly between the flat metal plate or frame C and the body of the churn, so that they turn on the heads as axes. The plate is slotted to receive the bolts when 40 they are placed in an upright position. At their outer ends the bolts are provided with thumb-nuts. It will be observed that this construction permits the bolts to swing inward and outward, so that when the lid is in 45 place they may be readily inserted into and removed from slots d^2 in its edge. The bolts e are formed with angular shanks, which pass loosely through similarly-formed openings in

the lid, so that they can be moved longitudinally therein. They are provided at their 50 lower ends with cross-heads and at their opposite ends with thumb-nuts. The lower edge of the frame is provided with notches e^2 to receive the bolts e , which fit snugly therein.

In applying the lid it is placed upon the 55 body of the churn with a sliding motion, the bolts e entering the notches in the lower edge of the frame. The bolts d are then swung upward into the slots in the lid and the thumb-nuts tightened. When the lid is to be removed, 60 it is only necessary to loosen the thumb-nuts on the bolts d , when they may be swung downward and the lid removed with a sliding motion from the body.

The advantage of my construction lies in 65 the fact that it is simple and permits the lid to be quickly applied and removed, and that the various parts are of such character that they may be easily kept clean.

Having thus described my invention, what 70 I claim is—

1. The churn-body provided with the side opening, in combination with the frame provided at the outer end with the open slots and at the opposite end with the laterally-movable 75 bolts, and the lid provided at the inner end with open slots and at the outer end with movable bolts, substantially as described and shown.

2. In a closing device for a churn, the metal 80 frame provided at one end with the open slots, the movable bolts mounted in the opposite end of said frame, and provided with thumb-nuts, the lid provided in one end with open slots to receive the above-named bolts, and the bolts 85 mounted in the opposite end of the lid in position to receive the bolts of the frame, and provided with nuts.

In testimony whereof I hereunto set my hand, this 13th day of December, 1889, in the 90 presence of two attesting witnesses.

ALBAN H. REID.

Witnesses:

WILLIAM L. MELONEY,
GABRIEL C. KNECHT.
